Attorney.

UNITED STATES PATENT OFFICE.

WALTER F. ROCKWELL, OF RANDOLPH, MASSACHUSETTS, ASSIGNOR, BY MESNE ASSIGNMENTS, TO HARVEY C. WHEELER, OF BOSTON, MASSACHUSETTS.

TOWEL-HOLDER.

1,319,796.

Specification of Letters Patent.

Patented Oct. 28, 1919.

Application filed December 23, 1918. Serial No. 267,928.

To all whom it may concern:

Be it known that I, WALTER F. ROCKWELL, a citizen of the United States, and a resident of Randolph, in the county of 5 Norfolk and Commonwealth of Massachusetts, have invented certain new and useful Improvements in Towel-Holders, of which the following is a full, clear, and exact specification.

10 The purpose of this invention is the effecting of improved means whereby a number of towels can be transported, stored and individually used, and yet be all the time attached one to the other so that they may 15 not be disconnected except when they are to be laundried. In accomplishing this I string the towels upon a chain or other suitable flexible connecting device fastened together at its ends after the towels have been 20 put thereon, the length of the chain being sufficient to permit any towel to be easily withdrawn from the others and conveniently used. For further convenience I provide a case or other device for supporting 25 the unused towels and also for receiving the used ones without disconnecting them from the chain.

In the drawings forming part of this specification, Figure 1 is a face view of a 30 case or cabinet embodying my improvements. Fig. 2 is a sectional side elevation of the same. Fig. 3 is a sectional plan view close to the top of the case. Fig. 4 is a diagram in perspective showing a few 35 towels strung upon a chain.

Referring to the drawings, the reference numeral 1 designates the back of a case designed to hold the bunch of towels; 2 the sides thereof, 3 the top, 4 an inclined shelf 40 intermediate of the top 3 and the bottom 6; 5 being narrow doors partially inclosing the space above the shelf, and 7 being a front partially inclosing the section below the shelf.

45 While I do not restrict myself to the doors 5 for partially inclosing the upper section of the case, it is desirable to have the doors suitably hinged and provided with locking devices, in order to retain the 50 towels within when the doors are closed, and to permit the convenient introduction of the fresh supply of towels. The doors should be narrow in order to leave the central parts of the towels free to be grasped

and the front one removed from the others. 55 The spring catches 10 shown in Fig. 2 serve to lock the doors in their closed position, and yet are convenient of access for unfastening the doors.

The towels 11 are each formed with a 60 suitable eye 12, preferably reinforced, through which the chain or other vinculum 13 is to be passed; after a suitable number of towels have thus been strung upon the chain, the ends of the chain being preferably 65 fastened together in any suitable manner, as by an easily separable link 14, or by a spring catch 14^a. This insures against the towels becoming separated either in transportation or in use, but especially the 70 latter.

At the center of the under surface of the top 3 is secured a hook 15, as shown in Fig. 2, upon which the chain should be hung, the towels resting upon the inclined shelf 75 and against the doors, while the excess of chain descends through a slot 16 in the front edge of the shelf into the space behind the front 7. A latch 17 swung down in front of the slot closes the latter against the too easy 80 pulling of the chain forward out of the slot when a towel is withdrawn for use.

As shown in Fig. 2, the shelf 4 is hinged at its rear edge 19 to the back 1 so that it can be swung upward to permit an easier 85 removal of the soiled towels from below it, suitable cleats 21 being provided for its support.

The object of the downward inclination 90 of the shelf 4 is to aid in pressing the towels forward against the doors 5, both to better support them and to present them where they can be more readily reached, so that a person wishing to use one thereof can easily take hold of the front one and pull 95 it away from the others and downward along the chain.

After being used, each towel is dropped into the receptacle 20 behind the front 7, sliding along the chain to the termination 100 of the latter's bend. By having the chain of a length to support the soiled towels out of contact with the bottom 6, the chain is held taut and by its pull on the unused towels aids in drawing them more snugly 105 against the doors.

After the towels have been used and a fresh supply is desired, the doors 5 are un-

fastened, the chain 13 is released from the hook 15, the shelf 4 is swung upward, and the entire bunch of soiled towels and the chain binding them together are bodily removed from the receptacle 20, and carried to the laundry. Here the chain is withdrawn from the towels, the link 14 being cut or the snap catch 14^a released in accordance with which it is employed, for permitting 10 such withdrawal, and the same are then laundered.

At the time the used towels are removed, a fresh bunch previously strung on its chain is stood upon the shelf 4, with the chain 15 caught upon the hook 15 and also depending through the slot 16 into the receptacle 20, and the doors 5 are closed and fastened.

Thus disposed, it is evident that the towels will not get lost, none can drop to 20 the floor to become trodden on and unduly soiled, none can be used for wiping off desks or washing windows, and at the same time they are convenient in use and handily transported and replaced.

Copies of this patent may be obtained for five cents each, by addressing the "Commissioner of Patents, Washington, D. C."

What I claim is:

1. A towel case comprising a shelf for supporting a bunch of towels, the shelf having a slot in its front edge, a removable device for inclosing said slot, means partially inclosing the towels in front, and a 30 flexible extended vinculum passing through the bunch of towels and through said slot and hanging in a loop beneath the shelf.

2. A towel case having two doors hinged to opposite sides thereof but spaced apart, 35 a shelf for supporting a bunch of towels behind the doors, a hook spaced above the shelf, the shelf having a closable slot in its front edge, and a chain passing through said towels and slot, the chain having its ends 40 fastened together and supported by said hook and hanging from said slot beneath the shelf.

In testimony that I claim the foregoing invention, I have hereunto set my hand 45 this 19th day of December, 1918.

WALTER F. ROCKWELL.
